WALL PANEL

John V. Nielsen, Chicago, Ill., assignor to Universal Equipment Company, Chicago, Ill., a corporation of Illinois

Application February 9, 1938, Serial No. 189,617

4 Claims. (Cl. 189—88)

This invention relates to wall and other panels and supporting means therefor.

It is an object of my invention to provide a decorative or other panel of substantial area yet suitably supported against warping or buckling.

It is another object to provide wall panels in a few shapes adapted to be combined to form a large variety of composite shapes or patterns.

It is a further object to provide wall panels with borders which at once reinforce the panels and constitute means for mounting the panels in place.

Another object is to provide a panel supporting construction adapted to securely mount one or more panels with the faces of the latter flush with the adjacent surfacing of the support.

A further object is to provide a wall panel mounting enabling one or more panels to be expeditiously and securely mounted.

It is also an object of my invention to provide a quickly attachable wall panel construction of any suitable outline adapted to afford a background for the attachment of posters, letters, emblems and other desired advertising matter.

Another object is to provide a wall panel structure adapted to bear striping for ornamental purposes and to match the baseboard of adjacent portions of the wall proper so as not to show mottled discolorations.

It is a still further object to so mount adjacent panels as to prevent swaying of the panels without detracting from their appearance.

Further objects and advantages of my invention will appear as the description proceeds.

The invention will be understood upon reference to the following description and the accompanying drawings, in which:

Fig. 1 is a fragmentary front elevation of wall paneling and supporting means involving the invention, certain panels being omitted to reveal details.

Fig. 2 is an enlarged fragmentary sectional view taken as indicated by the line 2—2 in Fig. 1.

Fig. 3 is a fragmentary front elevation similar to Fig. 1 but enlarged to show the structure with greater particularity.

Fig. 4 shows how the panels are placed prior to mounting on the supporting structure.

Fig. 5 is a fragmentary sectional view taken as indicated by the line 5—5 in Fig. 3.

Figs. 6, 7 and 8 are elevations of different wall patterns obtainable by using a few basic panel shapes.

Referring now more particularly to the drawings, I have illustrated at 15 a form of panel

constructed in accordance with the principles of my invention. This panel comprises a sheet of any suitable stiff material such as sheet steel or other metal of suitable thickness. The sheet preferably is shaped to provide a substantial area 18 which may be flat as shown or of spherical or other desired curved or other non-planar shape. In order to preclude warping or buckling, I spot weld or otherwise suitably secure the flanges 20 of reinforcing braces 21 to the back side 22 of the display section 18. The bars illustrated are channels, but it will be appreciated that angles or other shapes may be employed to like advantage.

Marginal reinforcement of the sheet is effected by bending flanges 24 backward and then forward into U shape so as to provide a body portion 25 connected to the section 18 and a free body portion 26 spaced inwardly from the portion 25 and resiliently joined thereto at the head or bight 27.

The panel section 18 is adapted for display purposes, and accordingly may be plated, enameled or otherwise surfaced and suitably ornamented by striping or otherwise.

The panel may be mounted on any suitable support, the wall 30 here shown being employed for illustrative purposes only. Attaching or anchoring clips 31, preferably of metal, are secured

30 by any suitable means 31a in the wall structure 30. Each clip may be formed in the shape of a T or otherwise, from either a single piece of material or a pair of angle bars 32, for example, welded or otherwise suitably joined to provide

35 a web 33 and flanges 34. A spring retainer strip 35 may have a flange 36 welded or otherwise suitably secured to each flange 34, and has a spring portion 37 extending in spaced relation to the web and terminating in a curl 38. The portion

40 37 is resiliently flexible relative to the flange 36, and the curl, when unstressed, is spaced from the adjacent web 33 somewhat less than the width of the bight 27 of the panel flange. The curl affords a cam surface 39 which converges

45 with the web 33 to provide a throat 40 and an entrance 41 sufficiently wide to readily receive the bight or head 27 so that the latter may be shoved in wedgingly in such manner as to force the portion 37 to yield, the head 27 being

50 snapped past the throat 40 and into the space or chamber 41 beyond the throat. The free body portion 26 of the panel flange is resiliently flexible about the head 27, and the spring part 37 is relatively stiff, so that when the head passes into the space 41 the curl 38 springs back toward its

normal position and in so doing forces the free portion 26 toward the portion 25.

The clip 31 may be coextensive with the flanges of the panels or only partly so, and a single clip or a plurality of clips may accommodate each flange. The spring strips 35 may be coextensive with the clip or a plurality of spaced strips may be mounted at each side of the web 33.

When the bight or head 27 is fully inserted, it preferably engages a flange 34 of the T clip, and the parts are preferably so dimensioned that the curl 38 at the same time engages the flange short of the inner side of the panel section 18. Now the panel flange is resiliently dove-tailed and therefore interlocked with the retainer clip against accidental displacement, and the panel is firmly held against rattling.

The border of the adjacent panel likewise cooperates with the retainer clip at the other side thereof so that the clip holds the adjacent margins of contiguous panels, the web 33 projecting between said margins and preferably terminating in an edge 44 substantially flush with the display surfaces 45 of the panels. The clips are preferably mounted to project forwardly from the supporting wall, as shown in Fig. 2, or may be free of any wall and be suspended, or supported on a stand. Or, if desired, the clips may be mounted in a recess in a supporting wall, and may have their outer edges flush with the outer surface of the wall, as shown, or project outward or set inward from said surface. The edges 44 of the webs 33 are preferably relatively narrow so as to be inconspicuous when the panels are attached. Only one side of the clip 31 is of course used at the free edge of the composite panel design or pattern. The webs 33 are preferably rigid so as to keep the panels from swaying.

It will be observed that in mounting a panel it is necessary merely to arrange its flanges in front of the entrances 41 and then shove the panel backward until its flanges are snapped in place. Thus the mounting is effected expeditiously.

Certain selected basic panel shapes are shown at 51, 52, 53 and 54 merely for the purpose of illustrating how, with a few shapes, a variety of composite area designs may be obtained. Although only three such designs have been illustrated, it is apparent even to an unskilled person how the panels of the shapes noted may be combined in various arrangements, employing as many of each as may be desired, to suit the fancy. Obviously other basic panel shapes will afford other varieties of composite shapes. One of many applications of the invention is in automobile filling stations, to provide attractive backgrounds upon which to post charts, posters and the like.

It is evident from the foregoing that I have provided a highly efficient, attractive and durable panel and inconspicuous supporting means therefor of extreme simplicity and economy of construction.

I am aware that reversals of parts may be

resorted to, and that numerous changes may be made and details of construction varied through a wide range without departing from the principles of my invention, and I therefore do not purpose limiting the patent granted hereon otherwise than as necessitated by the prior art.

I claim:

1. A structural wall panel member having an attaching portion comprising a relatively stiff head and a resiliently collapsible and expandible body connected to said head and adapted, when collapsed, to be of smaller lateral extent than said head, and a supporting member having an attaching portion adapted to receive and retain said head, said attaching portion comprising resilient means and normally forming a space preventing passage of said head but adapted to be enlarged as said head is forced in and resiliently flexes said means, said means being stiffer than said body and being operative, after said head has traveled through said space, to compress said body and thereby obstruct withdrawal of said head.

2. A wall construction comprising a support, panel-supporting bars connected to said support, each bar comprising a flange and a web projecting outwardly from said flange, and a panel having anchoring members projecting from a side of said panel, said bars having means securing said members in engagement with said webs and in substantially anti-rattling abutting relation to said flanges, said bars constituting the sole attaching means for said panel.

3. A structural wall panel member having an attaching portion comprising a relatively stiff head and a resiliently collapsible and expandible body connected to and at least as wide as said head and adapted, when collapsed, to converge from said head, and a supporting member having an attaching portion adapted to receive and retain said head, said attaching portion comprising resilient means and normally forming a space preventing passage of said head but adapted to be enlarged as said head is forced in and resiliently flexes said means, said means being stiffer than said body and being operative, after said head has traveled through said space to compress said body and thereby obstruct withdrawal of said head.

4. A connector of the class described, comprising a flange and a web, and a spring mounted on said flange and extending adjacent said web and providing with said web a spring socket for a member to be connected, said flange forming the inner extremity of said socket to abuttingly receive said member, said web extending outwardly beyond said spring in a direction transverse to said flange to guide said member into said socket in a direction transverse to and toward said flange, the entire web portion so extending lying in substantially the same plane as the socket-forming portion of said web, whereby the entrance to said socket is unobstructed.

JOHN V. NIELSEN.
